A. L. LUCAS.
COMBINATION TOOL.
APPLICATION FILED FEB. 10, 1919.

1,346,409.

Patented July 13, 1920.

UNITED STATES PATENT OFFICE.

AUGUST L. LUCAS, OF NEW HAVEN, CONNECTICUT.

COMBINATION-TOOL.

1,346,409.

Specification of Letters Patent. Patented July 13, 1920.

Application filed February 10, 1919. Serial No. 276,139.

To all whom it may concern:

Be it known that I, AUGUST L. LUCAS, a citizen of the United States, residing in the city and county of New Haven and State of Connecticut, have invented certain new and useful Improvements in Combination-Tools, of which the following is a full, clear, and exact description.

This invention relates to a combination tool of the geometrical instrument type, and more particularly to an instrument designed to be used by draftsmen in drawing straight and curved lines, although it will be apparent that this invention is well adapted for other uses.

The invention herein disclosed relates particularly to improvements in the tool which forms the subject matter of my Patent, No. 1,160,920, granted November 16, 20 1915.

One object of my invention is to provide an instrument of the type above indicated, having an arm with a blade slidably mounted thereupon, and to provide interengaging 25 means between the arm and blade to accurately position and retain the latter in any one of a plurality of positions longitudinally of said arm.

Another object of my invention is to provide graduated means whereby the blade pivotally mounted upon the arm may be accurately adjusted to any desired angle relatively to said arm.

To these and other ends the invention consists in the novel features and combinations of parts to be hereinafter described and claimed.

In the accompanying drawing:

Figure 1 is a plan view of my complete 40 combination tool.

Fig. 2 is an enlarged plan view of a portion of the device shown in Fig. 1.

Fig. 3 is a sectional view taken on the line 3—3 of Fig. 2; and

Fig. 4 is a rear view of the structure shown in Fig. 2.

In the embodiment of my invention, which I have illustrated in the drawing, I have designated by the numeral 10 a head 50 or base member having a graduated arm or straight edge 11 pivotally secured thereto by means of a screw or bolt 12. The head 10 is preferably provided with graduations 13,

which are positioned to coöperate with a pointer 14 formed upon the pivoted end of the arm 11. The arm 11 may be clamped in any desired angular adjustment relative to the head 10 by means of the clamping screw 15. If desired, the head 10 may be provided with levels 16 positioned in openings formed in this head. The pivoted arm 11 has a slot 17 formed longitudinally thereof adapted to receive a sliding bolt 18, which bolt is provided to secure the blade 19 to the arm 11 in any desired position of adjustment, the blade 19 being provided with a slot 20 through which the bolt 18 passes in order that the blade 19 may be adjusted both longitudinally and transversely of the arm 11. In order that the blade 19 may be pivotally secured to the bolt 18, so that the same may be swung about this bolt as a pivot, without being accidentally moved lengthwise, I provide the clamping element 21, which element is preferably provided with a disklike portion having a drill-hole formed therethrough to pivotally receive the bolt 18 and is provided with a radially projecting ear or the like 22, the object of which will be hereinafter described. The arm 11 preferably has a relatively wide groove 23 formed in its rear face, as shown in Fig. 4 of the drawing, in which groove is slidably mounted a substantially rectangular plate 24, which is rigidly secured to the rear end of the pivot bolt 18, the arrangement being such that the bolt 18 may be freely slid longitudinally of the arm 11 within the slot 17, but is prevented from rotating therein by the member 24 rigidly secured to the rear end of this bolt. The blade 19 is provided with a relatively wide groove 25 similar to the groove 23, just mentioned, and in this groove 25 is slidably mounted a block 26, which is rigidly secured to the rear end of a clamping bolt 27, which extends through a drill-hole formed in the radial extension 22, above mentioned, the arrangement being such that the block 26 and the graduated member 21 are mounted upon the pivot bolt 100 18 and they swing about this bolt as a pivot. If it is desired to rigidly clamp the blade 19 to the arm 11, this is done by simply tightening up the thumb nut 28, which is threaded upon the outer end of the pivot bolt 18. 105 If it is desired to draw a circle or arc by

inserting a pencil point or the like in the drill-hole 29, provided for this purpose, at one end of the blade 19, the thumb nut 28 is unscrewed sufficiently to permit the blade 19 to swing relatively to the arm 11, while at the same time, the blade 19 may be prevented from moving bodily relatively to the pivot pin 18 by tightening up the thumb nut 30, threaded upon the outer end of the clamping bolt 27, whereby the blade will be clamped between the spaced elements 22 and 26.

The construction, so far described, does not materially differ from the construction disclosed in my Patent No. 1,160,920, above mentioned. The improvement over my former device, just mentioned, will now be described. It should be noted that both the arm 11 and blade 19 are graduated, the graduations in the first case reading upwardly from the head 10, and the graduations upon the blade reading to the left from the pencil receiving hole 29. Upon the graduated member 21, above mentioned, is preferably formed a pointer 31, which coöperates with the graduations upon the arm and a similar pointer 32, which coöperates with the graduations upon the blade. It will, therefore, be seen that the blade 19 may be adjusted to any desired position relatively to the head 10 by shifting the blade longitudinally of the arm until the pointer 31 lies over the desired graduation. In order to provide means to assist in accurately positioning the blade 19, I have formed a number of spaced holes 33, positioned adjacent one edge of the slot 17, and upon the rear face of the block 24 I have pivotally mounted a spring clip 34, having a pin 35 mounted thereupon adjacent the outer end of the clip and projecting laterally therefrom in order that the same may be inserted in any one of the holes 33. The clip 34 is preferably mounted in a recess formed in the rear face of the block 24 and may be moved from the position shown in full lines in Fig. 4 to the dotted position in an obvious manner, a slot 36 being provided to clear the pin 35. The resiliency of the clip 34 will retain the pin 35 properly seated in any one of the holes.

In order that the blade 19 may be accurately adjusted to any desired angle relatively to the arm 11, I have provided the bolt 18 with a pointer 37, which is positioned to coöperate with the graduations upon the disklike member 21, the arrangement being such that when the blade 19 is swung angularly about the pivot pin 18, the graduated member 21 will be moved by the blade, whereas the pointer 37 will be prevented from rotating by means of the block 24, which is rigidly secured to the inner end of the bolt. The coöperation between the pin 35 and one of the holes 33, not only assists in properly positioning the blade 19 longi-

tudinally of the arm 11, but also prevents the bolt 18 and blade carried thereby from moving accidentally when the thumb nut 28 has been backed off sufficiently to permit the blade 19 to be swung about its pivot bolt, in the manner above pointed out.

What I claim is:

1. In a geometrical instrument, an arm, a blade slidably mounted thereupon, said arm having a plurality of sockets formed therein longitudinally of the same, a socket engaging element constructed to be moved into and out of engagement with any one of said sockets, and resilient means pivotally connected to said blade, said means having said socket engaging element secured thereto and movable thereby into and out of engagement with said sockets, said pivoted means arranged to swing said socket engaging element at right angles to the longitudinal axis of said element out of alignment with said row of sockets.

2. In a geometrical instrument, an arm, a blade slidably mounted thereupon, clamping means for securing said blade to said arm, said arm having a plurality of holes formed therein longitudinally thereof in spaced relation, a pin engageable with any one of said holes, and a flexible clip having said pin projecting laterally from one face thereof and constructed to yieldingly retain said pin in engagement with any one of said holes to thereby accurately position said blade longitudinally of said arm.

3. In a geometrical instrument, an arm, a bolt non-rotatably mounted upon said arm, a graduated member pivotally mounted upon said bolt, a blade slidably mounted upon said graduated member, means independent of said bolt for clamping said blade and graduated member together, whereby said blade is pivotally connected to said bolt and prevented from moving bodily relatively thereto, and a pointer upon said bolt coöperating with said pivoted graduated member.

4. In a geometrical instrument, an arm, a blade, a bolt non-rotatably secured to said arm for pivotally securing the blade thereto, interengaging means between said arm and an element carried by said blade whereby said blade is held against longitudinal movement relatively to said arm, a graduated element pivotally mounted upon said bolt, said graduated element provided with means for rigidly clamping said blade thereto, and a pointer carried by said bolt and coöperating with said graduations to indicate the angular adjustment of said blade relatively to said arm.

5. In a geometrical instrument, a slotted arm, a slotted blade, a bolt extending through said slots and constructed to clamp said blade in any desired position of adjustment upon said arm, means independent of the clamping elements of said bolt for se-

curing the bolt against movement within the slot of said arm, a graduated member pivotally mounted upon said bolt, means independent of said bolt for rigidly securing said graduated member and blade together, whereby said arm and blade may be angularly adjusted relatively to each other while

adjustment bodily is prevented, and a pointer carried by said bolt to coöperate with said graduated member.

10

In witness whereof I have hereunto set my hand on the 7th day of February, 1919.

AUGUST L. LUCAS.
